UNITED STATES PATENT OFFICE.

FREDERICK E. RAMSAY, OF WALSENBURG, COLORADO.

ELECTRIC-CURRENT REGULATOR.

SPECIFICATION forming part of Letters Patent No. 628,849, dated July 11, 1899.

Application filed October 14, 1898. Serial No. 693,529. (No model.)

To all whom it may concern:

Be it known that I, FREDERICK E. RAMSAY, a citizen of the United States, residing at Walsenburg, in the county of Huerfano and State of Colorado, have invented certain new and useful Improvements in Current-Regulators; and I do hereby declare the following to be a full, clear, and exact description of the invention, such as will enable others skilled in the art to which it appertains to make and use the same.

My invention relates to current-regulators, the same being in the nature of an improvement on the regulator patented to me September 6, 1898, No. 610,413, and especially designed for use in connection with electric lights using the alternating current, whereby the illuminating power thereof may be controlled, so that any degree of illumination within certain limits may be obtained.

The invention consists of a current-regulator in which the resistance-circuit is made up of an annular coil wound radially in layers and contact-plates in electrical connection with the separate layers, the said plates being adapted to be engaged in turn by a movable contact-maker.

The invention also consists in other details of construction and combinations of parts, which will be hereinafter more fully described and claimed.

In the drawings forming a part of the specification, Figure 1 represents a side elevation of my improved regulator shown in operative position in connection with a lamp and its socket. Fig. 2 is a vertical section through the regulator. Fig. 3 is a horizontal section taken on a line just beneath the lower edge of the upper disk of the regulator. Fig. 4 is a detail view of the core of the resistance-coil.

Like reference-numerals indicate like parts in the different views.

The socket-piece 1 and the lamp 2 may both be of any suitable form and construction.

The regulator 3 is designed to be located between the socket-piece 1 and the lamp 2 and is made up of two parallel disks 4 and 5, constructed of suitable insulating material, the disk 4 having secured to the upper side thereof a plug or tap 6, adapted to fit within the socket 1. The said tap 6 is made up of

an outer annular conductor 7 and has extending through it to the under side of the disk 5 a contact-rod 8, insulated from the sleeve 55 or conductor 7 by a block of porcelain 9, as clearly shown. The contact-rod 8 when inserted into the socket-piece 1 forms an electrical connection with one of the circuit-wires and the contact-sleeve 7 with the other 60 of the circuit-wires. Upon the under side of the disk 5 is secured a socket portion 10 for receiving the plug of the lamp 2, the same being provided with a contact-sleeve 11, which makes electrical connection with the outer 65 contact-sleeve of the lamp. Upon the upper side of the disk 5 is arranged a series of radially-extending contact-plates 12, 13, 14, and 15. Any number of these plates may be employed, but the number shown in the drawings is sufficient to enable a clear understanding of the invention to be had. The inner contact-plate 12 is in electrical connection by means of a pin or bolt 16 with the contact-sleeve 11. A standard 17 is located between 70 the disks 4 and 5, and in said standard is mounted one end of a threaded bolt 18, having a milled head 19 upon its outer end and a similar head 20 upon its opposite end. The head 20 fits within a socket or recess in the 80 standard 17 and is covered by a perforated plate 21, the said plate holding the threaded bolt 18 against longitudinal movement, but permitting the rotary movement thereof. The said bolt 18 extends through an internally-threaded contact-block 22, which is adapted to make electrical connection with one or the other of the contact-plates 12, 13, 14, and 15. Engaging one side of the bolt 18 is a spring 23, which is held in place against 85 the under side of the disk 4 and in electrical connection with the contact-sleeve 7 by means of a bolt 24. As thus constructed it will be seen that by turning the bolt 18 by means of the milled head 19 thereon the contact-block 90 22 will be caused to move in one direction or the other over the contact-plates 12, 13, 14, and 15.

In connection with the parts above described I employ an induction resistance-coil 100 25, made up of a central core 26, whose ends are insulated one from the other, as shown at 27, and a series of layers 28, 29, 30, and 31 of insulated wire wound upon said core. Each

layer of the coil is in electrical connection with each other layer through the contact plates or bars 12, 13, 14, and 15—that is to say, from the layer 28 of the coil a wire 32 leads to the 5 contact-plate 12, from the layer 29 a wire 33 leads to the contact-plate 13, and from the layer 30 a wire 34 leads to the contact-plate 14. Similarly a wire 35 leads from the contact-plate 15 to the layer 30, a wire 36 leads 10 from the contact-plate 14 to the layer 29, and a wire 37 leads from the contact-plate 13 to the layer 28, so that the inductive resistance of one or more of the layers of wire which make up the coil may be thrown into the circuit through the lamp-filament at will. For example, if it be desired to have the lamp burn with full force the contact-block 22 will be moved, through the agency of the threaded bolt 18, so as to make electrical connection 15 between it and the contact-plate 12. The circuit will then be through the contact-sleeve 7, bolt 24, spring 23, bolt 18, contact-block 22, bolt 16, sleeve 11, lamp-filament, and back through the contact-rod 8. If, however, it 20 be desired to decrease the illuminating power of the lamp the contact-block 22 will be moved so as to make electrical connection between it and one of the other contact-plates referred to—say, for example, contact-plate 25 14. The circuit will then be through the contact-sleeve 7, bolt 24, spring 23, bolt 18, contact-block 22, contact-plate 14, wire 36, layer of coil 29, wire 33, contact-plate 13, wire 37, layer of coil 28, wire 32, contact-plate 12, bolt 16, contact-sleeve 11, lamp-filament, and 30 contact-rod 8. A similar course will be followed whatever contact-plate the block 22 is thrown into electrical connection with.

From the foregoing description it will be 40 observed that I have devised a simple and convenient regulating device for an electric current, which may be applied to any lamp in use, by means of which the degree of illuminating power of the lamp may be controlled 45 at will by simply turning the milled head 19 of the threaded bolt 18. It will also be observed that I obtain the inductive resistance of the coil 25 by the peculiar method in which the windings thereof are made upon the core 26. 50 While I have stated in the foregoing description that one additional layer of the coil is thrown into and out of circuit during the successive movement of the contact-block 22 over the contact-plates 12, 13, 14, and 15, it

is obvious that the number of coils thrown 55 into or out of circuit may be increased—that is, instead of having one layer 28 connected to the contact-plate 12 by means of the wire 31 I may have two or more layers thus connected with said plate, and so on through the 60 whole series.

The construction of regulator shown and described is designed particularly for use with an alternating current. In order to convert the same for use with a direct current, 65 it is merely necessary to remove the induction resistance-coil and substitute known or ohmic resistance, substantially as shown in my former patent referred to.

Having now described my invention, what 70 I claim as new, and desire to secure by Letters Patent, is—

1. In a current-regulator, a resistance-circuit consisting of an annular coil wound radially in layers, and contact-plates in electrical connection with the separate layers of said coil, a contact-maker adapted to engage 75 said plates, and means for operating said contact-maker.

2. In a current-regulator, a resistance-circuit consisting of a soft-metal core whose ends are insulated from each other, a coil wound in layers thereon, and a series of contact-plates in electrical connection with the separate layers of said coil, and a contact-block 80 adapted to make electrical connection with one or the other of said contact-plates for throwing one or more of the layers of said coil into the main circuit.

3. A current-regulator for electric lamps, 90 comprising a pair of disks of insulating material, a socket-piece on one of said disks and a plug on the other, a series of contact-plates radially arranged between said disks, a core, and a coil of wire wound upon said core in 95 layers, said layers being in electrical connection successively with said plates, a contact-block adapted to make electrical connection with one or the other of said contact-plates, and a contact-spring for holding said contact-block in electrical connection with the contact-sleeve of the plug.

In testimony whereof I affix my signature in presence of two witnesses.

FREDERICK E. RAMSAY.
